UNITED STATES PATENT OFFICE.

JOSEPH S. GREENE, OF REEVES, LOUISIANA.

DESIGN FOR AN EYEGLASS.

Application filed October 11, 1921. Serial No. 507,149. Term of patent 14 years.

To all whom it may concern:

Be it known that I, JOSEPH S. GREENE, a citizen of the United States, residing at Reeves, in the county of Allen and State of Louisiana, have invented a new, original, and ornamental Design for Eyeglasses, of which the following is a specification, reference being had to the accompanying drawing, forming a part thereof.

The figure is a perspective view of eye glasses showing my new design.

I claim:

The ornamental design for an eye glass, as shown.

JOSEPH S. GREENE.
